UNITED STATES PATENT OFFICE.

CHARLES S. STRAIGHT, OF RANGER, TEXAS.

TOOL.

1,414,531.

Specification of Letters Patent. Patented May 2, 1922.

Application filed April 8, 1920. Serial No. 372,227.

To all whom it may concern:

Be it known that I, CHARLES S. STRAIGHT, a citizen of the United States, residing at Ranger, in the county of Eastland and State 5 of Texas, have invented certain new and useful Improvements in Tools, of which the following is a specification.

The object of the present invention is to provide an improved tool of the character 10 employed for lifting or recovering casings or pipes which have broken off or become lost in the well-hole of tubular wells.

A further object is to provide an implement of this character which may be 15 lowered into the well-hole for engagement with the casing sought to be recovered, improved means being embodied in the construction of the device whereby it may be expanded sufficiently to hold the casing 20 during the pulling or lifting of the same.

With these and other objects in view, the invention consists in the details of construction, combination and arrangement of parts 25 as will be hereinafter more fully set out and described, reference being had to the accompanying drawings wherein—

Figure 1 is a vertical longitudinal section of the improved steering device.

Figure 2 is a top plan view thereof, with 30 a cross section of the mandrel shown as taken on line 2—2 of Fig. 1.

Figure 3 is a cross section taken on the line 3—3 of Fig. 1 looking in the direction indicated by the arrows.

As more particularly pointed out in the specification following and as illustrated in the accompanying drawings, it is to be seen that this improved spearing or lifting tool is substantially embraced in three elements; 35 namely a cylinder, cylinder collar and a mandrel, made of steel or any other suitable material and turned to shape. In the drawings the numeral 1 designates the cylinder, of proper diameter and length for the object in view, and threaded externally 40 at its upper end with threads 2; which end is to be fitted into the collar of the spear. The cylinder is split longitudinally of its lower portion, and divided into an adequate 45 number of separate sections or pipe grips 4 depending from a point 5 near the upper end to allow for substantial expansion of the cylinder under the pressure of the mandrel as will hereinafter be more fully referred to. 50 Each section 4 has a tapered lower end 5' which coacts with the tapered ends of the

other sections to provide a pointed, or rather rounded, nose for the entire cylinder. As the pipe grips 4 are to be expanded into engagement with a pipe, for gripping and holding it, each one has corrugations cut 60 on the outside to form sharp teeth 6 which point upwardly so that as the cylinder is raised for lifting the pipe, the teeth will be caused to bite more firmly into the pipe and 65 thus hold it securely while it is being raised. The cylinder is to be fitted with a mandrel and for that purpose is provided with a smooth bore 7 of uniform diameter throughout the upper or solid end 1 of the cylinder 70 but tapering from the point 5 towards the nose from which result the fact that the pipe grips 4 are of substantial thickness, and therefore strengthened at their gripping ends, while the narrowed ends 8 render them 75 flexible and resilient. The upper edge of the bore is beveled as at 9 to enable the mandrel to be more easily and readily inserted in the cylinder after it has been lowered into hole of the well, the bevel edge 80 extending as will be noted out to the threaded edge.

Fitted to the cylinder 1 is the collar 10 having its bore 11 threaded for engagement with the threads 2 of the cylinder as illustrated. This collar is adapted to couple the cylinder to a supporting casing (not shown) by which it can be lowered into and lifted out of the well hole. This casing would be screwed into the upper end of the 85 collar and thus connected to the cylinder. The lower end of the collar forms a shoulder 12 which abuts against the edge of the casing or pipe to be pulled and into which the spear is inserted, the abutment 90 of this shoulder with the casing preventing the spear being lowered too far into said casing. The collar therefore, acts as a rest or support for centering the spear and for lining it up with the pipe or casing to be 95 removed from the hole.

The mandrel is formed with an elongated tapering shank 13 which fits the tapering portion of the cylindrical bore 7 and which is pointed at its extremity as indicated at 105 14, this shank serving to guide the mandrel into the bore of the cylinder. Above the tapered shank, the mandrel is provided with a straight stock 15 of uniform diameter 110 which has a sliding fit with the straight bored cylindrical portion 1. The stock is provided with a stud connection in the form

of a threaded end 16 formed integral with the stock at its outer end, the stud being of smaller diameter than the stock and tapering upwardly from the anvil shoulder 17 at its base for threaded engagement with an extension to be screwed thereon and by means of which extension the mandrel is properly supported and manipulated at considerable depth. After being lowered into the cylinder, the mandrel is driven in place by suitable tools, the driving blows falling upon the upper extension to which the mandrel is attached, but brunt of driving force is sustained by the anvil shoulder 17 of the mandrel against which the end of the extension which screws about the stud 16. The shock is then communicated to the strongest point of the mandrel, viz; the solid stock while the threads of the stud 16 are prevented by being distorted during the pounding action. As shown an enlarged head 6' is formed between the members 16 and said wrench neck 18. At a place appreciably removed from its shoulder 17 the stock is adequately reduced to provide a wrenchhold 18 square in cross section, or as represented in the present instance, cylindrical with its outer surface corrugated or otherwise roughened as at 19 to enable the wrench to secure a firm hold when turning the mandrel for threading the pin 16 into an extension as previously referred to. When disposed within the cylinder the mandrel is supported, as shown to advantage in Figure 1 of the drawings, with its stock embraced by the cylindrical portion 1 and its tapered guiding shank depending between the gripping sections 4 so that its pointed end 14 is in proximity to the open end of the nose of the cylinder. As the mandrel is forced further into the cylinder, the stock 15 will emerge from below the solid cylindrical portion 1 and cause the sections 4 to be spread apart, thus expanding the cylinder at its lower portion and causing the teeth of each section to bite into the pipe which it is desired to lift from the well hole. The stock, moreover, braces the sections rearwardly of their narrow or bending portions 8 during the period the sections are expanded.

In operation the device is connected by means of its collar 10 to a suitable casing or

extension and is lowered into a hole or well, minus the mandrel, until it enters the pipe or casing which is to be recovered; the shoulder of the collar resting upon the edge of such pipe or casing and supporting the cylinder therein. The mandrel is then lowered, preferably by means of a cable into the extension being guided by its shank portions and driven into the cylinder with tools, expanding the sections 2 and 4 until they are thought to have firmly gripped the pipe, subsequent to which the entire device is withdrawn from the well, carrying with it the broken off or lost pipe. In case it is found that the pipe cannot, for some reason or other be removed then the mandrel may be jerked out with the cable permitting the expanded sections to relax and thus free the pipe. The spear may then be drawn back to the top without the loss of any of its parts.

Although the foregoing may be said to comprehend the preferred embodiment of the invention, it is to be understood that such minor changes in the construction, combination and arrangement of parts, may be made as fall within the scope of the appended claim.

Having thus fully described my invention, what I claim as new and desire to secure by Letters Patent is:—

A device of the character described including a cylinder split longitudinally to provide a number of pipe grips each threaded exteriorly at the upper end and having its lower end rounded and provided with external teeth, a tapering bore being formed in said cylinder, a tapering shank arranged for co-action with said bore, having an extending wrench hold with corrugations, an enlarged head formed at the upper end of said shank terminating in an anvil portion from which extends a threaded stud and a threaded collar held to said cylinder whereby said cylinder may be brought into engagement with a suitable pipe, all substantially as and for the purposes set forth.

In testimony whereof I affix my signature in presence of two witnesses.

CHARLES S. STRAIGHT.
